Application February 17, 1934, Serial No. 711,644

7 Claims. (Cl. 201—55)

This invention relates to improvements in variable resistance devices of the type commonly employed as volume and tone control apparatus in radio sets, public address systems and the like.

More particularly this invention relates to terminals for variable resistance devices in which the resistance element is of the flat composition type against which the terminals are adapted to be clamped, and relates also, to a terminal cooperating with other means to make connection with a movable contact member.

This invention further relates to a combination variable resistance device of the aforementioned type and a switch or other associated device operatively connected to the variable resistance device for operation thereby when the contactor or other adjustable element is moved through a predetermined portion of its travel normally beyond the end of effective portion of the resistance element.

For some time, the radio trade has been demanding the smallest possible rheostat for volume and tone control purposes that can be furnished without sacrificing smoothness of operation or accuracy of the resistance gradient. In order to meet this demand it was necessary to reduce the width of the sector occupied by the resistance element end terminals and the movable contactor terminal to the lowest possible limit in order that the maximum length of effective resistance element might be maintained for useful variation in resistance.

In many cases it is also required that a power switch be added to the variable resistance device and be operated by angular movement of the operating shaft of the variable resistance device, usually through an angle adjacent one of the rotational limits of the movable contactor. Prior to the invention disclosed in my application Serial No. 692,665, filed October 7, 1933, it was common practice to operate the switch as the movable contactor of the variable resistance device approached one of the end terminals of the resistance element. However, to permit this, it was necessary to short circuit that portion of the resistance element traversed by the contactor during the switch operating portion of the contactor movement and as a result the expense of manufacture was increased and the effective portion of the resistance element was crowded into a much shorter space which greatly impaired the smoothness of control of the radio set.

While the above mentioned invention made available for operation of the switch, the portion of rotation during which the contactor was mov-

ing through the terminal sector on a part of the resistance element that could not be used otherwise, the present invention allows this to be done more satisfactorily as no portions of the terminal member lie in the path of the contactor and the contactor can be moved through 360° if desired.

Since no portion of the terminal lies in the path of movement of the contactor, there is no possibility of engagement between these members and hence the present invention eliminates any possibility of sudden variations in resistance due to transient metal to metal contact between the contactor and terminal, and also eliminates any possibility of the scoring of the polished surface of the contactor by the terminal.

It is well known that terminal members have been used to clamp onto wirewound resistance elements in various ways but none of them solved the above mentioned problems. In fact none of them were adapted to clamp onto a fragile resistance element of the composition type regardless of whether or not the other problems were solved.

One object of this invention is to provide a terminal for a variable resistance device that can be securely clamped in place so that no auxiliary holding means are required.

Another object of this invention is to provide a terminal that makes good electrical contact with the resistance element outside the path of the contactor and has no parts directly engageable by the contactor.

Another object of this invention is to provide a terminal with an ear that can easily be bent into contact with the resistance element without damaging the resistance element.

Another object of this invention is to provide a fixed terminal means for tapping the resistance element outside the path of the movable contactor and at a position intermediate the end terminals without appreciably affecting the total resistance of the resistance element and also providing a low minimum resistance between the terminal and the contactor.

Another object of this invention is to provide a terminal for the movable contactor which provides a positive electrical and mechanical connection with a member in the electrical circuit between the terminal and the movable contactor.

Another object of this invention is to provide a terminal that occupies an extremely narrow sector of the variable resistance device base.

Another object of this invention is to provide a combined variable resistance device and switch in which the switch can be operated while the

movable contactor is moving through the sector of the base of the variable resistance device occupied by the terminals.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated complete examples of the physical embodiment of my invention in which:

Fig. 1 is a plan view of the variable resistance device of my invention with the cover removed;

Fig. 2 is a partial elevational view in section taken along the line 2—2 of Fig. 1;

Fig. 3 is a sectional elevational view taken along line 3—3 of the rheostat shown in Fig. 1;

Fig. 4 is an isometric view of a partially completed terminal;

Fig. 5 is an isometric view of a terminal ready to be mounted on the rheostat;

Fig. 6 is an end view of one of the terminals of my invention assembled in place in the rheostat;

Fig. 7 is an elevational view of the terminal after assembly in the rheostat with the base and resistance element sectioned;

Fig. 8 is a view taken from the opposite end of that shown in Fig. 6;

Fig. 9 is a plan view of a part of the rheostat base showing notches and holes for mounting of terminals;

Fig. 10 is an isometric view of a partially completed terminal of slightly modified construction;

Fig. 11 is an end view similar to Fig. 8 of a slightly modified terminal;

Fig. 12 is an isometric view of one element of a two piece terminal;

Fig. 13 is an isometric view of the other element of the two piece terminal;

Fig. 14 is a side view of a two piece terminal assembled in the rheostat, with other parts of the rheostat shown in section;

Fig. 15 is an enlarged portion of Fig. 14 showing the bent over end of the terminal;

Fig. 16 is a plan view of the terminal of Fig. 14 assembled in the rheostat;

Fig. 17 is an elevational view, with some parts broken away, of a rheostat with a switch mounted on the cover and adapted to be operated by rotation of the rheostat shaft;

Fig. 18 is a sectional plan view of the rheostat and switch operating member taken along the line 18—18 of Fig. 17;

Fig. 19 is a partial plan view showing the movable parts in a certain position;

Fig. 24 is a reduced bottom plan view showing the base with terminals attached; and

Figs. 25 and 26 are enlarged fragmentary plan and sectional views respectively showing a detail of a modified construction.

Referring to the drawings more in detail, the variable resistance device 1 comprises a base 2

formed of insulating material, such as a phenol condensation product, or the like, on which is mounted a resistance element 3, which may be formed by coating a strip of heavy paper with a carbonaceous conductive composition. In other cases the resistance element may preferably be formed by applying the conductive coating directly to the base 2. Usually it is desirable to deposit a low resistance coating on the section of the resistance element that will be engaged by terminals 4 and 5 so that a low minimum resistance between the terminal and the movable contactor can be obtained. These low resistance coatings are preferably tapered in thickness at the ends so that there will be no sudden change in the rate of resistance variation as the movable contactor passes from one section to the other, as is shown and described in my copending application Serial No. 666,444, filed April 17, 1933. End terminals 4 and 5 make connection with the ends of the effective portion of the resistance element 3 and provide a means of connecting an external circuit with the ends of the resistance element.

A movable contactor 6 is pressed into contact with the resistance element 3 by the pressure arm 7 which terminates in a tip 8 that is tapered to engage the edges of the hole 9 in the contactor 6 so as to accurately position the latter on the resistance element. The pressure arm 7 is positioned on the drive plate 10 by two diametrically opposed ears 11 and 12 formed up from the body portion of the arm 7 on a center line which is at 90° to the center line passing through the tip 8 so as to engage two corresponding notches on the drive plate 10. The drive plate 10 is secured to the shaft 14 through the co-operation of a flattened reduced end 15 on the shaft 14, a hole of corresponding shape in the drive plate, and a washer 16 fitted over the reduced flattened end 15 of the shaft 14 and the flattened end peened over to hold the members all in pressure engagement.

Centrally located in the base 2 is a bushing 17 having a shoulder 18 which is knurled around its outer portion to provide teeth which penetrate the surface of the base 2 when the bushing is pressed into place. On the other side of the base

2 is a washer 19 that fits over another shoulder 20 on the bushing. The base 2, bushing 17 and washer 19 are all held securely together by swaging the shoulder 20 of the bushing into engagement with the washer 19. Preferably the washer 19 has a tapered hole formed with the large end away from the base so that the portion of the shoulder 20 that extends beyond the washer 19 before swaging, can be swaged into the hole 55 leaving the mounting surface substantially planar. The shaft 14 is journaled in this bushing 17 and is positioned longitudinally by a shaft collar 21 and washer 22 bearing against one end of the bushing 17 and opposing the thrust between the drive plate 10 and the bushing 17 which is exerted by a spring member 23 located between the drive plate 10 and the pressure arm 7. This spring member is spaced from the shaft by projections on the rim that form notches 65 which engage the ears 11 and 12 bent up from the body portion of the pressure arm 7. The body portion of the pressure arm 7 is pressed against a collector ring 24 that is insulated and spaced from the bushing by a washer 25 of fibre 70 or other suitable material and connected to the terminal 27 by a reduced section 26' of tail 26 extending through a hole 28 in the ear 29 of the terminal 27.

As the shaft 14 is rotated, the drive plate 10

drives the pressure arm 7 which is in engagement with the contactor 6 so that the contactor is moved along the resistance element and passes very close to the bent over ear 50 of the tap terminal 48 and, when no switch is used, the drive plate 10 strikes a suitably positioned stop ear, not shown but similar to 85 (Fig. 18), projecting in from the cover 80 so that the contactor 6 comes to rest between the bent over ears 31 and 32 of terminal 4 at one end of rotation. Rotation in the other direction is limited by the drive plate 10 striking the stop ear 85 and bringing the contactor to rest between the bent over ears 45 and 46 of terminal 5.

Referring more particularly to the terminals of my invention, it is to be noted that they may be brought very close together and yet allow a sufficient spacing between terminals to provide the necessary insulation and also to provide a maximum effective length of resistance element. I have accomplished this by tapering the body section of the terminal so that the angle occupied by the terminal is approximately the same or in some cases slightly more at the outer end than at the inner end, which provides sufficient strength at the outer portion to withstand the forces that may be imposed during attachment of a conductor. This same effect could be obtained by any means of narrowing the inner end of the terminal such as by providing one or more steps in width of the body portion. The inner end, where great strength is not required, is much narrower and is adapted to be clinched over onto the base or resistance element to hold the terminal in place and in the case of the end terminals, also make contact with the resistance element.

Referring more in detail to Figs. 4 to 8, the terminal comprises a terminal proper or body portion 36 which is formed with a head portion 38 having laterally extending wings 38', 38'' constituting shoulders, an upturned end portion 34, and an upstanding ear 35. Integral with and extending from the head portion 38 of the terminal 36 is a connection extension (commonly called at "solder lug") having a perforated portion 33 and a neck 44 of reduced width. Adjacent the tip 31 of the upturned end 34 is a reduced section or neck 43 and adjacent the tip 32 of the ear 35 is a reduced section or neck 37.

This terminal 4 can be easily manufactured by punching a piece out of sheet brass or other suitable material to shape shown in Fig. 4 with the exception that the ear 35 sheared out of the body portion 36 and formed at right angles has no reduced section 37. A separate trimming operation is employed to cut notches out of the sides and create this reduced section 37 that serves to force the bending line to the desired point when the tip 32 is bent over on the resistance element.

Another forming operation gives the terminal of Fig. 4 the shape shown in Fig. 5, the shape in which it is positioned on the base. The extending wings 38' and 38'', formed on a head portion 38 of the terminal proper 36 are hooked over the lobe 39 which is integral with the base 2 and extends beyond the periphery of the cover (Fig. 18) to act as a terminal support. The terminal is then slid into the notches 40 and 41 in the base until the end 34 starts to enter the hole 42 in the base 2. The body portion 36 of the terminal 4 is then pushed up against the under side of the base 2 so that the tips 31 and 32 of the end 34 and the ear 35 project beyond the face of the resistance element 3. When in this position the reduced sections 43 and 37 extend slightly

below the surface of the resistance element 3 so that when the tips 31 and 32 are bent over onto the resistance element 3, their contacting surfaces will be substantially parallel with the surface of the resistance element 3 when they meet the latter, due, as previously stated, to the bends occurring at a point predetermined by the location of the reduced sections. The reduced sections also permit the end 34 and the ear 35 to be bent over onto the resistance element 3 with a more even and accurately predetermined pressure than would otherwise be possible. Thus a uniform contact pressure between the terminal 4 and the resistance element 3, and consequently, a uniform contact resistance between these elements can readily be obtained. Furthermore the provision of reduced sections makes it possible to obtain these results without damage to the very thin and fragile conductive coating of the resistance element.

The thickness of this coating is in most cases only one or two thousandths of an inch and as a result the resistance element can be very easily damaged by any excessive pressure on any part of its surface such as would be created by the surface of the terminal ears meeting the conductive coating unevenly as they are bent over into their final position.

The exact width, length and position of these reduced sections necessary to force the bending to occur in them without distorting other parts of the ears and to allow the end to be brought into firm coplanar contact with the resistance element over the maximum area depends largely upon the kind and thickness of metal used for the terminal and can best be determined by trial.

Where it is desired to provide a variable resistance device having an extremely low contact resistance between the terminal and the resistance element, a soft pad of conducting material is interposed between these elements.

Such an arrangement is shown in Figs. 25 and 26 wherein a pad 90 is constituted of soft sheet metal or metal foil having originally a U shape and is inserted in the openings 41d, 42d and 45 pushed up against the base 2d. The terminal 4d is then inserted in a manner similar to that described in connection with the terminal 4 and the tips 31d, 32d are bent over to clamp the ends 91, 92 of the pad 90 against the contact surface 50 of the resistance element 3d.

As the pad 90 is soft it adapts itself to the contours of the surfaces of the resistance element 3d and the terminal 4d respectively and thus has an area of intimate contact with both members 55 respectively which is greater than the area of contact between the terminal and resistance element when these latter elements are in direct contact and no pad is employed.

An equivalent result may be obtained by interposing between the resistance element and the tips which are bent over against the resistance element a section of soft wire, such as fuse wire; when the tips are bent over to clamp the terminals on the base, the interposed wire is flattened out into intimate contact with the surface of the resistance element and the tips. This wire thus serves as a cushion for the tips and provides a low contact resistance between the terminal and the resistance element.

No auxiliary parts are required to hold the terminal in place against the resistance element as this is accomplished by the tips 31 and 32 of the end 34 and ear 35 respectively that are bent over onto the resistance element 3 clamping the ter-

terminal 4 tightly to the base 2 and making good electrical contact with the resistance element 3.

The reduced portion 44 in the connection extension is provided so that it will bend and thereby prevent damage to the variable resistance device if any excessive bending force is applied to the connection extension, such as might occur when leads to the external circuit are being connected.

10 Any side thrust applied to the connection extension is resisted by the sides of notches 40 and 41 and sides of hole 42 bearing against the sides of the terminal. Pressure on the connection extension in a direction parallel to the axis of the shaft 14 is resisted in one direction by pressure of extending wings 38' and 38'' against the lobe 39 of the base 2 and by a light pressure of the back part of the terminal body 36 against the underside of the base 2. With pressure in the other direction there will be a slight pressure increase of the bent over tip 31 on the resistance element 3 and a pressure of the body portion 36 adjacent the notch 40 upward against the base 2.

In Figs. 10 and 11 I have shown another method of obtaining a reduced or weakened section in the upstanding ear and upturned end to position the bending line at a point that will allow the tips to bend over onto the resistance element and accomplish the same results outlined above.

30 The reduced section is provided in this terminal 104 by piercing a hole 137 in the ear 135, and a hole 143 in the ear 134 at suitable positions. All other parts of the terminal function in exactly the same manner as described above.

35 Another modification of the terminal is shown in Figs. 12 to 16. In this form of terminal the ears that extend through the base are creased transversely to definitely locate the bending line instead of having a section cut away as in the
40 previously described forms, and two pieces are used so that together they function in a manner similar to the terminal 4. A member 204 (Fig. 12) is punched from sheet metal and portions of each end formed up so that when it is in place
45 on the base 2b (Fig. 14) before the clinching operation has been performed it will have the shape shown by the dotted lines. When in this position the ear 234' projects into the hole 42b in the base 2b and fits closely against the wall of the hole
50 closest to the outer rim of the base 2b. The other ear 235 on this member fits snugly against the inside wall of the notch 41b in the base and the creased section 237 falls at a position that permits bending the tip 232 over against the resistance element 3b and making good contact with it over the maximum area and without damage
55 to the conducting surface.

A second flat member 204' (Fig. 13) is punched from sheet metal and formed as shown in Fig. 14. 60 with the tip 231 of ear 234 in the position shown by the dotted lines. Member 204' is placed in position with the wings 238' and 238'' of the terminal bearing against the upper side of the lobe 39b, the body portion 236 against the body portion 65 236' of the member 204, and the ear 234 extending up through the hole 42b in the base 2b and fitting snugly against the ear 234' of the member 204. The creased section 243 is at a point that permits bending the tip 231 into firm engagement with and over a maximum area of the resistance element 3b. In other respects the parts of this two piece terminal function in the same manner as the corresponding parts of the single piece terminals. 70 75 All of the parts are made of sheet metal.

75 All of the above terminals have the tips long

enough to bend over onto the resistance element as far as possible and still fall short of the path of movement or race-way of the contactor by several thousandths of an inch. This provides two very short paths between the contactor and the terminal when the contactor is between the terminal ears and allows a very low minimum resistance to be obtained and also allows the contactor to be moved past the terminal if desired, without touching it or producing any discontinuity in the nature of the contact between the contactor and the surface of the resistance element, such as might occur if the contactor made direct contact with the terminal.

When a switch is to be used in combination with the variable resistance device, the switch is preferably located so that it is not engaged while the contactor 6 is being moved from the effective portion A of the resistance element 3 (Fig. 18), to a position between the ears 31, 32 of terminal 4 as shown in Fig. 21, at which point the effective portion of the resistance element 3 ends. However, at this point a pin 84 on the drive plate 10 engages an operating member 82 of a switch 81 mounted on the cover 80 of the variable resistance device. For constructional details of this switch, reference may be made to my co-pending application Serial No. 699,490, filed November 24, 1933.

Movement of the contactor 6 on past the terminal 4 onto the portion B operates the switch 81 so that the latter is thrown into the open circuit position before the stop ear 85 in the cover 80 is engaged by the drive plate 10. When the switch 81 is in the open circuit position and the drive plate 10 is against the stop 85 the contactor 6 will be in the position shown in Fig. 20. The portion of the resistance element 3 over which the contactor 6 travels during operation of the switch 81 and which is ineffective to produce any variation in the effective resistance furnished by the variable resistance device 1, may have a very low resistance coating deposited on its surface so that the effect on the external circuit will be practically the same as though the contactor 6 were short circuited to the adjacent end terminal 4 or, when this effect is not desired, a high resistance coating may be applied to the resistance element 3 over this range. If desired, the coating may be terminated at or just beyond the terminal 4 by providing a wider section 95 which carries no conductive coating, so that the contactor 6, when moving through the greater part of the switch operating portion of its travel, does not engage the conductive surface of the resistance element. 55

When the drive plate is rotated in the opposite direction the switch operating member 82 is engaged by the pin 84, and the switch 81 is thrown to the closed circuit position before the contactor 6 passes out from between the terminal ears 31, 32 and onto the effective portion A of the resistance element 3. When the shaft 14 is rotated to its limiting position in this same direction the stop ear 85 will be engaged by the other side of the stop portion of drive plate 10 at which time the contactor 6 is directly between the bent over ears 45 and 46 of terminal 5 as shown in Fig. 23. 60 65

It is often desirable to provide a fixed tap connection on the resistance element at a point intermediate the end terminals and when this is desired a terminal of the type shown in Figs. 7, 11 or 14 can be used. An extension or lobe 41 (Figs. 1 and 22) is provided on the base 2 and is notched for terminal 48 similar to the man- 75

ner in which lobe 39 is notched for either of the end terminals 4, 5. The terminal 48 is assembled in the same manner as the end terminals 4, 5 except that the ear 49 closest to the center of the base 2 is not bent over onto the resistance element 3 but is bent over onto the insulating base 2 instead. In order that no appreciable amount of the resistance between the end terminals 4, 5 be short circuited, only the outer ear is bent into contact with the resistance element 3.

If the inner ear 49 were bent over onto the resistance element 3 a considerable proportion of the total resistance would be short circuited since the inner marginal portion of the resistance element 3 is the shortest and provides the lowest resistance path between the end terminals 4, 5 and consequently exerts the greatest influence on the overall resistance of the resistance element 3.

When a very low minimum resistance between the tap terminal 48 and the movable contactor 6 is desired a low resistance composition is deposited, prior to the assembly of the tap terminal 48, on that portion of the resistance element 3 where the tap terminal 48 is to be located. Preferably this low resistance coating 51 (see Fig. 18) is applied in the general shape of a triangle with the base at the outer rim of the resistance element 3 where the ear 50 of the tap terminal 48 will be clinched over and with the apex of this triangle toward the center of the variable resistance device 1. In most cases it is desirable that the edges of this low resistance coating 51 be tapered so that there will be no sudden change in the rate of resistance variation as the movable contactor 6 moves onto or off of this section of the surface of the resistance element 3. With the low resistance coating 51 applied in this general shape and position no appreciable amount of the effective resistance of the resistance element 3 is short circuited and a very low minimum resistance is obtained between the contactor 6 and the tap terminal 48 when the contactor 6 is adjacent the tap terminal 48 and bearing on the low resistance coating 51. The distance that the apex of the low resistance triangular sector 51 is made to extend toward the ear 49 will depend upon the conditions desired.

The terminal 27, electrically connected to the movable contactor 6, is also of the clinch-on type which permits rapid assembly and requires no auxiliary parts to hold it in place. The connection extension 57 has a reduced section 58 which will bend before the base 2 or any other part of the terminal 27 is damaged by a bending or twisting force applied to the end of the terminal 27, such as might occur when a wire is being attached to the terminal 27. The extending wings 60 and 61 bear against the upper side of lobe 39 on base 2 when the portion 63 is seated in the notch 64 in the lobe 39 of base 2 and the body portion of the terminal 27 bears against the other side of the base 2. The end 29 of the terminal 27 is bent up from the body portion 62 and extends through the hole 67 in the base 2 fitting snugly against the outer edge of this hole. Approximately even with the inner surface of the base 2 is a hole 28 in the end 29 and beyond is a tip portion 68 clinched over against the base 2. The collector ring 24 has a tail 26 formed as shown in Fig. 3 that terminates in a reduced tapered section 26' which is projected through the hole 28 in the terminal 27 so that the shoulder on the tail 26 at the base of the reduced section 26' bears against the terminal adjacent the wall of the hole 28. The tip 68 of end 29 is then

bent over onto the base into the position shown in Fig. 3. This securely clamps the reduced section 26' of the tail 26 under the terminal and also locks the section 26' into the hole 28 due to the sides of the hole squeezing in against the sides of section 26' when the ear is bent over. Thus a connection of low electrical resistance and great mechanical strength is formed between these members with a minimum of parts and labor.

I claim:

1. A variable assistance device comprising a base, a plurality of apertures in said base, a resistance element comprising a support and a conductive film carried by said support, disposed on said base between said apertures and having a relatively smooth contact surface, a terminal for said resistance element extending between said apertures and having portions registering therein for effecting self-clamping engagement with said base and said resistance element, and adjustable contacting means engageable with said resistance element for varying the effective resistance of the device.

2. A variable resistance device comprising a base, a plurality of apertures in said base, a resistance element comprising a support and a conductive film carried by said support, disposed on said base between said apertures and having a relatively smooth contact surface, a terminal extending between said apertures having portions registering therein for engaging said base, said portions being bent over into clamping engagement with the conductive film of said resistance element, and adjustable contacting means associated with the contact surface of said resistance element for varying the effective resistance of the device.

3. A current controlling device comprising a base having a recess in a peripheral portion, a wire connecting terminal mounted on said base, said terminal having a body portion mounted on one side of said base and extending to seat in said recess, a shouldered portion bearing against the other side of said base adjacent the recess, a wire connecting portion extending from said shouldered portion away from said other side of the base, and means extending through said base for securing said body portion to said base.

4. A current controlling device comprising a base having a recess in the peripheral portion thereof and a terminal seated in said recess, said terminal having a shouldered portion engaging a first face of said base, a wire connecting portion extending from said shouldered portion away from said first face of said base, and a body portion extending along the second face of said base and extending through an opening in said base, the end of said body portion being bent over toward said base to clamp said end against said base.

5. A variable resistance device comprising a base, a resistance element comprising a support and a conductive film carried by said support, disposed on one surface of said base, a contactor engaging the surface of said resistance element, means for moving said contactor over the surface of said resistance element, and a terminal secured to said base and having a body portion extending along the under surface of said base and a contact portion extending through said base and bent into engagement with the upper surface of said resistance element, said terminal having a reduced transverse cross-sectional area provided at the point of bending, adjacent said contact portion.

NEWTON C. SCHELLENGER.

CERTIFICATE OF CORRECTION.

Patent No. 2,138,210.

November 29, 1938.

NEWTON C. SCHELLENGER.

It is hereby certified that error appears in the printed specification of the above numbered patent requiring correction as follows: Page 5, second column, line 11, claim 1, for the word "assistance" read resistance; and that the said Letters Patent should be read with this correction therein that the same may conform to the record of the case in the Patent Office.

Signed and sealed this 7th day of February, A. D. 1939.

Henry Van Arsdale.

(Seal)

Acting Commissioner of Patents.
